UNITED STATES PATENT OFFICE

ALBERT STANLEY, OF NEWTON, ILLINOIS

DESIGN FOR A DOLL

Application filed May 1, 1930. Serial No. 35,458. Term of patent 8½ years.

To all whom it may concern:

Be it known that I, ALBERT STANLEY, a citizen of the United States of America, residing at Newton, in the county of Jasper and State of Illinois, have invented a new, original, and ornamental Design for a Doll, of which the following is a specification, reference being had to the accompanying drawing, forming a part hereof.

In the drawing:

Figure 1 is a view in perspective of a doll showing my design, the doll being viewed from the front, and

Fig. 2 is a similar view showing the doll from the rear.

I claim:

The ornamental design for a doll, as shown.

ALBERT STANLEY. [L. S.]
